US0D1071618S

(12) **United States Design Patent** (10) **Patent No.:** **US D1,071,618 S**
Chen (45) **Date of Patent:** **** Apr. 22, 2025**

(54) **TABLE**

(71) Applicant: **EASY TRADING TECHNOLOGY DEVELOPMENT CO. LTD**, Tianjin (CN)

(72) Inventor: **Xin Chen**, Tianjin (CN)

(73) Assignee: **EASY TRADING TECHNOLOGY DEVELOPMENT CO. LTD**, Tianjin (CN)

(**) Term: **15 Years**

(21) Appl. No.: **29/854,601**

(22) Filed: **Sep. 27, 2022**

(51) **LOC (15) Cl.** **06-06**

(52) **U.S. Cl.**

USPC **D6/707.23**; D6/707.19

(58) **Field of Classification Search**

USPC D6/329, 641, 647, 651, 655, 655.18, D6/655.19, 655.22, 656, 656.1, 656.13, D6/656.14, 656.18, 685, 691, 691.1, D6/691.2, 691.5, 691.6, 691.9, 691.7, D6/694, 694.1, 702, 707, 707.18, 707.19, D6/707.23

CPC A47B 21/06; A47B 37/00; A47B 13/08; A47B 17/00

(57) **CLAIM**

The ornamental design for a table as shown and described.

DESCRIPTION

FIG. 1 is a front perspective view of a table, showing my new design;

FIG. 2 is a rear perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a partial enlarged view of FIG. 1;

FIG. 9 is a partial enlarged view of FIG. 2; and,

FIG. 10 is a partial enlarged view of FIG. 7.

The broken lines in the figures are for the purposes of illustrating portions of the table, which form no part of the claimed design.

1 Claim, 10 Drawing Sheets
